[57] **CLAIM**

The ornamental design for a hexagonal vertical jet mound, as shown and described.

DESCRIPTION

FIG. 1 is a top plan view of a hexagonal vertical jet mound, showing our new design;

FIG. 2 is a side view thereof;

FIG. 3 is a side view thereof, rotated 30 degrees from the view in FIG. 2;

FIG. 4 is a top plan view thereof, the broken line showing of the spa is for illustrative purposes only and forms no part of the claimed design;

FIG. 5 is a top plan view of a modified embodiment of FIG. 1;

FIG. 6 is a top plan view thereof, the broken line showing of the spa is for illustrative purposes only and forms no part of the claimed design;

FIG. 7 is a perspective view of the hexagonal vertical jet mound of FIG. 1;

FIG. 8 is a bottom plan view thereof, with the jets removed from the mound;

FIG. 9 is a perspective view of FIG. 5; and,

FIG. 10 is a bottom plan view thereof with the jets removed from the mound.
